UNITED STATES PATENT OFFICE.

FRANK BEATTIE, OF DETROIT, MICHIGAN.

VENDING-MACHINE.

1,395,941.

Specification of Letters Patent.

Patented Nov. 1, 1921.

Application filed September 24, 1919. Serial No. 325,843.

To all whom it may concern:

Be it known that I, FRANK BEATTIE, a citizen of the United States of America, residing at Detroit, in the county of Wayne 5 and State of Michigan, have invented certain new and useful Improvements in Vending-Machines, of which the following is a specification, reference being had therein to the accompanying drawings.

10 This invention relates to a vending machine, and has special reference to that class of machines for dispensing packages, parcels and articles that can be conveniently placed in stacked formation, for instance, 15 packages of tobacco.

The primary object of my invention is to provide a machine of the above class wherein novel package holders are employed and made adjustable so as to accommodate packages of various sizes, the holders maintaining packages in stacks or piles so that packages may be withdrawn from the base of each stack or pile, thus providing a gravity feed for the packages with assurance that 25 there is always a package in position to be delivered by the machine.

Another object of this invention is to provide a package dispensing machine embodying holders or reservoirs from which 30 packages are alternately withdrawn, and to accomplish this a novel delivery slide member is employed adapted for normally retaining a package to be delivered by a reciprocatable movement of said slide member 35 in either direction. Associated with the slide member is a novel tension device which prevents accidental movement of the slide member.

A further object of this invention is to 40 provide a machine of the above class having a slide or delivery member which is coin-controlled, that is, the vending machine is adapted to receive a coin so that the slide or delivery member may be operated, otherwise the slide or delivery member is locked and packages cannot be surreptitiously obtained.

A still further object of my invention is to 45 provide a vending machine in which different kinds of packages or articles may be placed, and in some instances the machines may be arranged in a battery formation and thus permit of a large variety of packages or articles being at all times retained convenient for a customer.

A still further object of my invention is

to provide a package dispensing machine wherein the parts are constructed with a view to reducing the cost of manufacture and at the same time retain those features 60 by which durability and ease of assembling are secured. With such ends in view my invention resides in the novel construction to be hereinafter described and then claimed.

Reference will now be had to the drawings, wherein—

Figure 1 is a longitudinal sectional view of a portion of the machine;

Fig. 2 is a perspective view of the machine;

Fig. 3 is a plan of a portion of the machine showing one position of the delivery members;

Fig. 4 is a similar view showing another position of a delivery member;

Fig. 5 is a perspective view of a portion of the vending machine, illustrating one of the units thereof;

Fig. 6 is an enlarged cross sectional view of a portion of the coin-controlled mechanism; and

Fig. 7 is a perspective view of a temporary coin holder.

In describing my invention by aid of the views above referred to, I desire to point 85 out that the same are intended as merely illustrative of the vending machine as now constructed and used, and I do not care to confine my invention to the precise construction and arrangement of parts, other than 90 defined by the appended claims.

The machine as best shown in Figs. 1 and 2 comprises an oblong casing having side walls 1, a front wall 2, a bottom wall 3, a hinged or detachable lid 4 and a rear wall 95 (not shown). The hinged lid 4 permits of easy access being had to the interior of the casing and said lid may be retained in a closed position by a conventional form of lock, generally designated 5.

The casing is supported in an elevated position by legs 6 and the front wall 2 is of greater depth than the side walls 1 so that its lower edge will be in proximity to a delivery chute 7 mounted between the front 105 legs 6 and connected to the bottom wall 3, as at 8, so that the upper end of said chute will communicate with openings 9 in the bottom wall 3 through which packages pass when being delivered by the machine.

The casing as now constructed contains two units, which as far as the operation of

the machine is concerned, are independent of each other, but from a structural standpoint the units depend on each other for support, particularly when considering the package holders, but since the units are identical in construction, I deem it only necessary to specifically describe one of said units.

- Each unit includes two package holders, arranged one in advance of the other within the casing and each package holder comprises a transverse partition 10 vertically disposed within the casing and connected to the side walls 1 thereof. Disposed parallel to the upper and lower edges of the partition 10 and connecting the side walls 1 are transverse bars 11 having slots 12 longitudinally alining with slots 13 in the upper and lower edges of the partition 10 and extending into the slots 12 and 13 are stud bolts 14 carried by longitudinal parallel vertically disposed partitions 15. These partitions have the upper and lower ends thereof, adjacent the rear edges, provided with a series of openings 16^a to receive stud bolts 16 carried by the upper and lower ends of a partition 17. Nuts 18 may be screwed on the stud bolts 14 and 16 to hold the partitions 15 and 17 in adjusted positions relative to the partition 10 and the bars 11. It is through the medium of the adjustable partitions 15 and 17 that the area of the holder may be increased or decreased to receive packages or parcels and maintain the same in stacked or piled formation, as best shown in Fig. 1. The packages are designated 19 and are adapted to be withdrawn one at a time, from the bottom of the holder, with the lower most package resting on the bottom wall 3 or a delivery member on said bottom wall.
- 40 The delivery member comprises an oblong horizontally disposed frame 20 having the rear end thereof provided with a tension board 21 and its forward end with a housing 22, said board and said housing normally engaging guide blocks or guide brackets 23, carried by the bottom wall 3, so that the delivery member may be reciprocated by an operating rod 24 connected to the housing 22 and extending through the front wall 2 of the machine casing. The operating rod 24 has a suitable knob or handle which permits of the delivery member being pushed inwardly or drawn outwardly, when released.
- 45 The tension board 21 has longitudinal 55 grooves 25 and slots 26 and engaging said tension board are the ends 27 and 28 of a coiled spring 29 loosely supported on a transverse rod 30, carried by brackets 31 mounted on the bottom wall 3, said rod serving as a support for the spring of an adjoining unit. As shown in Fig. 5 the spring end 27 engages in one of the grooves 25 of the tension board and the other spring end engages the extreme rear end of said board. The spring 29 is therefore maintained under tension and

holds the delivery member in its outermost position, so that said member cannot accidentally slide. When the delivery member is pushed inwardly by the rod 24, the spring end 27 rides in its groove until it encounters the slot 26 of the tension board, when it extends through said slot, while the spring end 28 engages in its groove. The ends of the spring therefore alternately serve to hold the tension board at its shifted position, and the bottom wall 3 is slotted, as at 32, to provide clearance for the ends 27 and 28 of the spring 29.

In the housing 22 and attached to the forward end of the frame 20 is a ratchet bar 33 having heads 34 and 35. The ratchet bar is longitudinally slotted, as at 36, and one edge of said bar is formed with teeth 37 and a cam 38, the purpose of which will hereinafter appear.

The bottom wall 3 has an opening 39 and adjustable in said opening is a coin receiving member 40 which is adjustably held between angle bars 41 connected to the lower side of the bottom wall 3 and extending transversely of the machine casing. The coin receiving member 40 has a coin passage 42 to receive a coin 43 admitted thereto through a chute 44 extending from the upper end of the passage 42 to a coin slot 45 in the front wall 2 of the machine casing, said coin slot being above a window 46 in the front wall 2. The coin receiving member 40 is recessed; as at 47, to receive a pivoted pawl 48 normally engaged by a spring 49 which is adapted to retain the lower end of a pawl in engagement with the coin 43 and the upper end of a pawl in engagement with the ratchet bar 33 or the heads 34 and 35 thereof.

With the upper end of the pawl 48 engaging the head 35, as shown in Fig. 5, it is necessary for the delivery member to be pushed inwardly before the coin 43 can be released. And when said coin is released, as will hereinafter appear, it is deposited in a chute 50 extending to the front wall 2 of the machine casing, said chute terminating above a pivoted spring pressed coin holder or gate 51, best shown in Fig. 7. The coin holder or gate is adapted to temporarily hold the coin 43 at a small window 52 in the front wall 2, so that a customer can determine when the coin has been properly used.

Extending inwardly from the holder or gate 51 is an arm 53 to which are connected cables 54 extending through hangers 55 carried by the bottom wall 3. The upper ends of the cables 54 are connected to the lower ends of levers 56 fulcrumed in bearings 57 of the bottom wall 3, so that the upper ends of said levers will extend through openings 58 in the bottom wall 3 and into the slot 36 of the delivery member. Retractable springs 59 are connected to the lower ends of the levers 56 to maintain said levers

normally vertically disposed and in the path of the heads 34 and 35 of the ratchet bar 33.

A receptacle 60 is suitably mounted in the delivery chute 7 against the front wall 2 of the machine casing, so as to receive coins released by the holder or gate 51, and access is had to the receptacle 60 through a suitable door way in the side wall of the chute 7, said door way being normally closed 10 by a door 61, as best shown in Fig. 2.

Considering the operation of the machine, with the delivery member in the position shown in Figs. 1 and 5, the lowermost package in the forward package holder rests on 15 the bottom wall 3 and in the forward end of the frame 20, while the lowermost package in the rear package holder rests on the tension board 21 of said delivery member. With the coin 43 engaging the lower end of 20 the pawl 48 the upper end of said pawl will be held so that it cannot engage the teeth 37 of the ratchet bar 33, when the delivery member is pushed inwardly, but if no coin is in engagement with the lower end of the 25 pawl 48, then the spring 49 forces the upper end of the pawl into engagement with the teeth 37 when the delivery member receives its initial inward movement. Further movement of the delivery member is 30 prevented by the teeth 37 and consequently the delivery member cannot be successfully operated without a coin being in the machine. Again assuming that the coin holds the pawl 48 the cam 38 will eventually impinge against the upper end of the pawl 48, retract the lower end of the pawl against the action of the spring 49, and release the coin 35 43 so that it may descend in the chute 50 to the temporary holder or gate 51.

On the initial movement of the delivery member the coin previously held within the holder or gate 51 is released to enter the receptacle 60 and this is brought about by the head 34 of the ratchet bar 33 engaging the 40 upper end of the forwardmost pin 56, tilting said pin until it engages in front of the head 34 by which time the holder or gate 51 is closed to receive the next coin.

After the cam 38 actuates the pawl 48 to 45 release the coin 43, the upper end of the pawl recedes over the forwardmost teeth 37, which are reversely disposed relative to the rearwardmost teeth 37 and as the delivery member moves inwardly the lowermost package in the forwardmost holder is shifted over the opening 9 and passes through said opening into the delivery chute 7 from where it may be obtained at the front wall 2 of the machine. The machine 50 having delivered a package is now left with

the head 34 engaging the upper end of the pawl 48 and when another coin is deposited in the machine the delivery member may be pulled outwardly to transfer a package from the rearmost holder to the opening 9, the 65 package having automatically dropped into the rear end of the frame 20 during the previous operation of the machine. On the rearward stroke of the delivery member the foremost pin 56 is actuated to open the temporary coin-holder or gate 51 and in this manner one of the pins actuates the temporary coin holder on an inward stroke of the delivery member and the other pin actuates the temporary coin holder on an outward 70 stroke of the delivery member.

Considering the two units shown in Fig. 3 it is apparent that four different sizes of packages may be housed within the single machine casing but it is preferable to provide only for two sizes, so that similar packages will be delivered for coins of like denomination. However, various combinations can be worked out and with the machines in battery formation it is possible to 80 vend or dispense a large variety of articles.

What I claim is:—

1. The combination with a vending machine, of package holders therefor, each holder comprising a slotted stationary partition, a slotted bar, longitudinal apertured partitions between said bar and said stationary partition, and stud bolts carried by said partitions and adjustably held in the slots of said bar and stationary partition, 90 and adjustable partition between said longitudinal partitions, and stud bolts carried by said adjustable partitions and engaging in the apertures of said longitudinal partitions, so that the area of said holder may be increased and decreased.

2. In a vending machine, a reciprocatable delivery member comprising an oblong frame, an operating rod supported from one end thereof, a slotted and grooved tension board at the opposite end of said frame, and a spring supported adjacent said board and having end convolutions alternately engaging in the grooves of said board and one end of said spring adapted to engage 105 in a slot of said board so that said spring is constantly under tension to hold said member against accidental movement.

In testimony whereof I affix my signature in the presence of two witnesses.

FRANK BEATTIE.
